Inventor:

John Nusbaum

UNITED STATES PATENT OFFICE.

JOHN NUSBAUM, OF ALLIANCE, OHIO.

IMPROVED CAR-TRUCK.

Specification forming part of Letters Patent No. 55,850, dated June 5, 1866.

To all whom it may concern.

Be it known that I, JOHN NUSBAUM, of Alliance, in the county of Stark and State of Ohio, have invented certain new and useful Improvements in Railroad-Car Trucks; and I do hereby declare that the following is a full and complete description of the same, reference being had to the accompanying drawings, making a part of this specification, in which—

Figure 1 is a side elevation of a car-truck. Fig. 2 is an end view. Fig. 3 is a view of the under side.

Like letters of reference refer to like parts in the several views.

A A' represents the frame of the truck, constructed in the ordinary way. B B are the wheels, and C C the shafts or axles.

Underneath each side of the truck, between the wheels, is a shoe, D, made of heavy plate-iron, and bolted to the under side of the frame. The shoe is much wider than the thickness of the wheels, and projects on each side, as shown in Figs. 2 and 3, on the inside equal to about the thickness of the wheel and on the outside to the extent of the frame of the truck, as represented. The shoe is made of one piece of iron, the ends of which are divided, and then inclined upward in opposite directions, as seen in Fig. 1, forming braces E and F, that are bolted to the under side of the frame of the truck. The inside braces, F, are the widest, and are bolted to the cross-piece A' of the frame. These braces, as arranged, render the

shoe very strong and firm in its position, suspending it till within a few inches of the face of the rail. The side edges of the shoe are bent or turned downward, forming flanges e, as shown in Figs. 2 and 3.

The object of this shoe as constructed and arranged is for the purpose of preventing the car from upsetting or turning when the axles break or the wheels get off in any way, for, if one or more of the axles break or wheels get off, the car, instead of falling over on the ground, would be upheld and supported by the shoes, which, being only about four inches from the rail, will drop down upon it, and the car will be retained in nearly an upright position, and will slide along upon the rail on the shoes. The flanges e on the sides of the shoes prevent them from sliding off the rails, and they also act as a brake when thus sliding along on the rails, aiding in bringing the train to a stop, and prevent the tearing up of the ties, should the train leave the track, by thus sliding along over them.

What I claim as my improvement, and desire to secure by Letters Patent, is—

The shoe D, with the flanges e and braces E F, in combination with the truck, in the manner and for the purpose set forth.

JOHN NUSBAUM.
